BAG BOTTOMING MACHINE

John S. Davis, Scarborough, N. Y., assignor to Equitable Paper Bag Co., Inc., Long Island, N. Y., a corporation of New York

Application March 9, 1956, Serial No. 570,481

8 Claims. (Cl. 93—14)

The present invention relates generally to the manufacture of paper bags and more particularly to an improved machine for efficiently forming the bottom of a paper bag.

In machines for making what in the trade is known as "shopping bags," the bag is fabricated from a flat web of kraft paper or other suitable material. This web is then formed into a tube and perforated into sections, one end of each section being folded and closed so as to constitute a so-called satchel bottom. In making a bag closure of this type, a bag tube section is usually provided with a pair of parallel slits extending inwardly from the bottom edge of the section. The end plies or opposing faces of the tube section to be closed are then separated and folded into a diamond to form the closure. The same bottoming technique is also used in the making of sacks and other types of bags in which each face is constituted by one or more plies.

One problem involved in forming the closure stems from the fact that the two plies or opposing faces of the tube section are superimposed when flat and they cannot readily be separately gripped for opening. To facilitate the opening up of the end plies, it has heretofore been the practice to cut out a notch in the paper web which, when the web is tubed, occupies a position extending inwardly from the end of the section. This notch makes it possible to grip one ply of the tube section with a mechanical finger or clip which clears the other ply through the notch therein, the other ply being held by pins whereby the finger and pins act to spread open the tube.

This expedient has several drawbacks. In cutting out the notches in the tube, small squares of kraft waste paper are formed which fall to the floor or are scattered in the vicinity of the machine. In a high production bag-making machine, this waste paper is created in large quantities and must be repeatedly cleared from the area of the machine to prevent interference with its operation. Moreover, the existence of a notch in the satchel bottom of the bag somewhat weakens the bag closure and represents a structural disadvantage at the very point where strength is a primary consideration.

Another prior technique to facilitate the separation of the faces of the section has been to cut slits at the top end of one section, leaving a tab extending from the bottom end of the adjacent section, which tab may be gripped by a clamp to spread the plies in forming the bottom. When the finished bag which includes the extending tab is employed in automatic filling apparatus, there is a tendency for the tab to snag in the apparatus, thereby loosening the bottom. Another disadvantage of this technique is the presence of a notch in the upper end of the finished bag which in some instances may mar the appearance of the bag.

Accordingly, it is the principal object of the present invention to provide a shopping bag having a satchel bottom closure which overcomes the above-noted draw-

2

backs and in which no discontinuities exist in the structure of the bottom, the top and bottom edges being perfectly even and free of tabs and notches.

More specifically it is an object of the invention to 5 provide a bag bottoming machine in which an indented tab is formed in the end of the tube section to facilitate the opening thereof, said tab forming a temporary notch and later being pasted into the closure to fill in said notch whereby the strength of the closure is unimpaired. 10 In a bag in accordance with the invention, no waste is created and the machine is capable of operating at high speed.

Briefly stated, in a bag making machine in accordance 15 with the invention, the flat web is perforated to form separable sections, a tab being cut inwardly from the bottom edge of the section and being pushed down to form a temporary notch. The flat web is then shaped into a flattened tube having two single plies or two opposing faces each composed of several plies. The flattened tubular section is then separated from the web at the perforation line and parallel slits are cut into both plies or faces of the section on either side of the tab. Thereafter the plies or faces are spread apart and folded 20 to form a diamond having flaps defined by said slits. 25 Finally, the flaps are folded over in superposed relation to complete the satchel bottom. In spreading apart the plies, a clamp which clears the temporary notch formed by the pushed-down tab in one ply is adapted to grip the other ply, the tab being restored to its initial position 30 when said flaps are folded over to eliminate all discontinuities to the bottom structure.

For a better understanding of the invention, as well 35 as other objects and further features thereof, reference is had to the following detailed description to be read in conjunction with the accompanying drawing wherein:

Fig. 1 is a schematic view showing successive stages A to E of operation in a bag machine in accordance with the invention.

Fig. 2 is a continuation of Fig. 1 and shows the remaining stages F to H of the machine including the final bottoming stage.

Fig. 3 is a plan view of the flat paper web as it enters the tubing stage of the machine.

Fig. 4 is a plan view of a separated tubular bag section prior to the formation of the bottom closure.

Fig. 5 is a plan view of the bag section in the first step of forming the bottom closure.

Fig. 6 is a plan view showing the next step of forming the bottom closure.

Fig. 7 is a plan view showing the final step of forming the bottom closure.

Fig. 8 is a perspective view of the dies for slitting the tab in the tube section.

Fig. 9 is a perspective view of the bending element for pushing down the tab to form a temporary notch.

Fig. 10 is a perspective view of the delivery drum and the clamp thereon for opening the bottom of the bag section.

Fig. 11 is a perspective view of the delivery drum and rollers cooperating therewith for folding the flaps of the bottom closure.

Fig. 12 is a side view of a tubular bag section entering the bottoming drums.

Fig. 13 is a side view showing the tubular bag section after it leaves the bottoming drum to ride about the delivery drum.

Fig. 14 is a side view showing the delivery drum as it acts in conjunction with a chain driven roller for closing one flap of the bottom.

Fig. 15 is a side view showing the delivery drum as

it acts in conjunction with another roller to close the other flap of the bottom.

Referring now to the drawing, and more particularly to Fig. 1, at the input end of the paper making machine, a flat web 10 of kraft paper drawn from a roll or any other material to be formed into bags, is fed at a first stage A into a perforator constituted by an upper cylinder 11 having a perforator bar 12 secured thereto, the upper cylinder cooperating with an idler 13 formed by a rubber covered roller. Perforation lines 14 are impressed transversely on the web at equidistant positions thereon. The spacing between successive perforations 14, as shown in Fig. 3 determines the length of the web section 15 to be formed into a tube, and this spacing depends on the diameter of cylinder 11. Cylinders of different diameter may be provided for tube sections of different length. Conventional drive means may be used to impart travel to the web 10.

From perforator stage A, the flat web 10 is fed to a tab slitter, at stage B, constituted by a periodically actuated holder 16 supporting a pair of parallel blades 17 and cooperating with an anvil roller 18 which may be made of steel. The periodic reciprocation of the tab slitter is controlled relative to the continuously moving web so as to form two spaced slits extending inwardly from the perforation line at the lower edge of the section 15, the slits defining a square tab 19.

From tab slitter, in stage B, the flat web feeds into a handle patch applicator in stage C in which a strip of patch material 20 and a cord handle 21 is supplied to cooperating rollers 22 and 23 so as to apply two spaced handles adjacent the perforation line 14 at the top of the end bag section. The handle applicator, per se, constitutes no part of the present invention and is disclosed only to show how a complete shopping bag is fabricated in all of its details. Of course, in other types of bags without handles, the applicator stage may be omitted.

The flat web from applicator stage C then enters a tab bender stage D including a rotary timed pusher or paddle 24 which is adapted to push down tab 19, as best seen separately in Fig. 9, thereby forming a temporary notch clearance at the bottom of the bag section. From the tab bender the flat web enters a tubing stage E of conventional design in which the web is shaped into tubular form 25 and the edges adhesively joined, as shown in Fig. 3, the tab 19 standing up outside the tube. The tubular web leaving the tubing in a flattened state.

The next stage F is shown in Fig. 2 and it includes a pair of feed rollers 26 and 27 which supply the flattened tubular web 25 into cooperating pinch rollers 28 and 29 provided with pinch bars 30 and 31, the pinch rollers running at a slightly retarded rate relative to the web movement so that the web lies lax between the feed rollers and the pinch rollers at the moment of snap-off to be later described.

From the pinch rollers the flattened tubular web is fed into larger and somewhat faster snap-off cylinders 32 and 33, at a stage G, provided with coating pinch bars 34 and 35. When the flattened tubular web 25 is gripped by the pinch bars 34 and 35, the greater speed of cylinders 32 and 33 with respect to rollers 28 and 29 applies a longitudinal stretching force to the web, snapping off the tubular section at the perforation line 14. The separated section thereupon enters a bag bottom slitter including dies 36, which, as shown in Fig. 4, cut parallel slits 37 extending longitudinally from the bottom edge on either side of tab 19, the slits cutting through both plies or opposing faces of the section against a roller 38.

From slitting stage G the flattened tubular section enters the final or bottomer stage H where the bottom edge of the section 25 is inserted between a delivery drum 39 and a bottoming drum 40 cooperating therewith. As shown separately in Fig. 10, the flattened tubular section 25 is constituted by two plies 25a and 25b, the tab 19 being formed in ply 25a. Projecting from the periphery

of drum 39 is a clamping finger 41 which is adapted to engage ply 25b and to clamp it against the surface of the drum, the finger clearing ply 25a through the temporary notch formed by tab 19. Ply 25a, on the other hand, as shown in Fig. 12, is impaled on bottomer drum 40 by means of pins 42 projecting radially therefrom. Thus as the two drums rotate in opposing directions, the two plies are drawn apart and folded into a diamond to form the satchel bottom.

Before considering the mechanism for forming the satchel bottom, we shall first consider the various folding operations necessary to complete the bottom as illustrated in Figs. 5 to 7. When the two piles 25a and 25b of section 25 are separated, as shown in Fig. 5, a diamond is formed which includes two generally rectangular flaps X and Y whose edges are defined by slits 37, flap X having tab 19. Paste is supplied to the open diamond by conventional paste bars along the path indicated by the dashed lines 43.

Then flap X is folded down about a crease line 44, the bottom assuming the configuration shown in Fig. 6. Finally, flap Y is folded down about crease line 45, the flap Y overlapping flap X, as shown in Fig. 7. It is important to note that in folding down flap X, the tab 19 is restored to its original position and there is no discontinuity or notch in the surface of the bottom.

As shown in Fig. 12, when the plies 25a and 25b are spread apart by drums 39 and 40, the sides of the tubular section are folded in along the slit lines 37 to form the diamond. The operation of clamp finger 41 is controlled by a follower 46 which rides on a stationary arcuate cam surface 47 to cause the clamp finger to retract, as shown in Fig. 13, when the bag section rests on top of drum 39. Thus in the course of each rotation of drum 39, the finger 41 is sequentially opened and closed. Crease bars or tucker blades 48 are provided to introduce the required crease lines 44 and 45 in the diamond about which the flaps fold.

To fold over flaps X, a roller 49 is provided which is supported between two continuous chains 50 and 51, the chains being driven by wheels 52 and 53 at a speed about twice that of the delivery drum 39 whereby roller 41, which runs over the tube section 25 in the same direction as drum 39 but twice as fast, acts to press down fold X against the surface of the drum. It is to be understood that the invention is not limited to a 2:1 speed ratio, and other overspeed relationships may be used. Fold Y is folded over fold X by a roller 60 rotatably supported at a fixed position which bears against the surface of the delivery drum, as shown in Fig. 15. The completed bag finally passes through discharge rollers 54 and 55.

Before the bag section on the delivery drum 39 is released by the clamping finger, a clamping bar 56 mounted on the drum cooperates with the tucker blades 48 to pinch the bag section at its crease lines and thereby maintain the bag on the drum after the finger releases same. Clamping bar 56 is controlled by a spring-biased lever 57 having a follower 58 operating on a stationary cam 59 to effect successive clamping and release operations of the clamping bar in the course of drum rotation.

While there has been shown what is considered to be a preferred embodiment of the invention, it will be manifest that many changes and modifications may be made therein without departing from the essential spirit of the invention. It is intended, therefore, in the annexed claims to cover all such changes and modifications as fall within the true scope of the invention.

What is claimed is:

1. In a bag making machine wherein a flat web is perforated at spaced transverse positions to form web sections, means to form a tab in said flat web section extending inwardly from the bottom edge thereof, means to push down said tab to form a temporary notch, means to shape said flat web section into a flattened tube having two opposing faces, means to form slits in both faces on

either side of said tab extending inwardly from said bottom edge, and means to separate said faces and to fold same to form a diamond having flaps defined by said slits, said separating means including a clamp clearing said temporary notch to grip one of said faces.

2. In a bag making machine for converting a continuous paper web into a tubular bag having a satchel bottom, the combination comprising means to perforate said flat web at spaced transverse positions to form web sections, means to form a tab in said flat web section extending inwardly from the bottom edge thereof, means to push down said tab to form a temporary notch, means to shape said flat web into a flattened tube having two plies, means to form slits in both faces on either side of said tab extending inwardly from said bottom edge, and means to separate said plies and to fold same to form a diamond having flaps defined by said slits, said separating means including a clamp clearing said temporary notch to grip one of said plies, and means to fold over said flaps to complete the bottom.

3. In a bag making machine for converting a continuous paper web into a tubular bag having a satchel bottom, the combination comprising means to perforate said flat web at spaced transverse positions to form web sections, means to form a tab in said flat web section extending inwardly from the bottom edge thereof, means to push down said tab to form a temporary notch, means to shape said flat web into a flattened tube having two plies, means to separate said section from said web, means to form slits in both plies on either side of said tab extending inwardly from said bottom edge, means to spread apart said plies and to fold same to form a diamond having flaps defined by said slits, said separating means including a clamp clearing said notch to grip one of said plies, and means to fold over said flaps to complete the bottom, said last-named means restoring said flap to its initial position.

4. In a bag making machine, means to impart travel to a bag-forming flat web, a perforator to form spaced transverse perforations in said flat web to form bag sections therein, a tab slitter to cut a tab inwardly from the bottom edge of said section, a tab bender to push down said tab to form a temporary notch, a tubing device to form said flat web into a flattened tube having opposing plies, a bag bottom slitter to form parallel slits in both plies of said tube on either side of said tab, and means to spread apart said plies including a first rotary drum having a finger thereon clearing said notch and gripping one of said plies, and a second rotary drum operating in the reverse direction and having pins to impale the other ply, said plies being folded to form a diamond having flaps defined by said slits.

5. In a shopping bag making machine, means to impart travel to a bag-forming flat web, a perforator to form spaced transverse perforations in said flat web to form bag sections, a tab slitter to cut a tab inwardly from the bottom edge of said section, a tab bender to push down said tab to form a temporary notch, a tubing device to form said flat web into a flattened tube, snap-off cylinders to separate said tube from said web, a bag

bottom slitter to form parallel slits in both plies of said tube on either side of said tab, means to spread apart said plies including a delivery drum having a finger clearing said notch and gripping one of said plies, and a bottoming drum having pins to impale the other ply, said drums rotating in opposing directions, said plies being folded to form a diamond having flaps defined by said slits.

6. A shopping bag making machine comprising means to impart travel to a bag-forming flat web, a perforator to form spaced transverse perforations in said flat web to form sections, a tab slitter to cut a tab inwardly from the bottom edge of said section, a tab bender to push down said tab to form a temporary notch, a tubing device to form said flat web into a flattened tube, snap-off cylinders to separate said tube from said web, a bag bottom slitter to form parallel slits in both plies of said tube on either side of said tab, means to spread apart said plies including a delivery drum having a finger clearing said notch and gripping one of said plies, a bottoming drum having pins to impale the other ply, said drum rotating in opposing directions, said plies being folded to form a diamond having flaps defined by said slits, and means to fold over said flaps, said last-named means restoring said tab to its original position.

7. A bag making machine for forming bags having satchel bottoms comprising means to impart travel to a bag-forming flat web, a perforator to form spaced transverse perforations in said flat web to form sections, a tab slitter to cut a tab inwardly from the bottom edge of said section, a tab bender to push down said tab to form a temporary notch, a tubing device to form said flat web into a flattened tube, snap-off cylinders to separate said tube from said web, a bag bottom slitter to form parallel slits in both plies of said tube on either side of said tab, means to spread apart said plies including a delivery drum having a finger clearing said notch and gripping one of said plies, and a bottoming drum having pins to impale the other ply, said plies being folded to form a diamond having flaps defined by said slits, and means to fold over said flaps including a first roller travelling peripherally along said delivery drum in the direction of rotation thereof but at a relatively high speed, and a second roller rotatably mounted at a stationary position and bearing against said delivery drum, said first roller folding down one flap, said second roller folding down the other flap to overlap the first flap, said first roller restoring said tab to its initial position.

8. A machine, as set forth in claim 7, wherein said first roller is supported between a pair of continuous chains moving at an overspeed relative to said delivery drum.
